MANUALLY OPERATED TRAVELING
BARRIER CARRIER

Turner C. Rush, Lexington, Ky.

Application May 7, 1934, Serial No. 724,428

1 Claim. (Cl. 119—15.5)

This invention relates to a traveling race track barrier and has for the primary object the provision of means whereby a barrier may be manually moved from one place to another at a track 5 for the purpose of lengthening or shortening a race as to a desired distance and which provides a viewing stand for the starter equipped with means to permit the starter to release the barrier from said stand.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a transverse sectional view illustrating my invention associated with a race track. Figure 2 is a fragmentary side elevation illustrating one side of a car and showing the same mounted to a track.

Figure 3 is a similar view showing the opposite side of the car. Figure 4 is a diagrammatical view showing the wiring diagram of this invention.

Figure 5 is a fragmentary horizontal sectional view showing one of the barrier posts and barrier strap carriage mounted thereto and which forms 30 the subject matter of a copending application hereinafter identified.

Figure 6 is a fragmentary vertical sectional view illustrating the same.

Referring in detail to the drawings, the numer- 35 al 1 indicates a race track having a fence 2 located at opposite sides thereof and positioned along the track and upon the outside of the fence are barrier tracks 3 which are adapted to extend a de- 40 sired distance so that a barrier mounted thereon 10 can be manually moved along the track 1. Each barrier track consists of vertically arranged posts 4 preferably of metallic construction mounted to a foundation 5' and the posts carry upper and lower rails 5 and 6 each of angle iron construction. 45 Mounted to travel upon the barrier tracks 3 are cars 7 each including a substantially triangular shaped body 8 of hollow formation which provides an inclined wall having brackets to releasably secure to said wall barrier posts 9. The 50 brackets of the cars support the barrier posts 9 in converging relation so that they incline towards the track 1 and have slidably mounted therein carriages 12a to which is releasably secured a barrier strap 11 constructed of an elastic mate- 55 rial and tensioned when applied to said carriages

so that when said carriages are released they will travel towards the upper end of the posts 9. The carriages are releasably held by electrically actuated catches 10. The barrier strap 11, carriages 12a and catches 10 form the subject matter of a co-pending application filed November 27, 1933, 5 and Serial No. 699,947 and shown in Figures 5 and 6 of this application.

Each car 7 has horizontally arranged axles 12 on which are journaled wheels 13 that ride upon the upper rail 5. The car body also has secured thereto arms 14 to which are journaled pairs of rollers 15 engaging with opposite faces of the upper and lower rails 5 and 6. The rollers 15 act as guides for maintaining the wheels 13 upon the upper rail and provide a construction whereby the car may be conveniently moved along the track by a person pushing or pulling on a handle bar 16 secured to the car.

Either of the cars may have removably mounted thereon a starter's platform 18 provided with a suitable railing 19 having an entrance closed by a removable chain 19'. The flooring of the platform rests upon the upper edge of the car body and has legs 20 secured thereto which are in turn 25 removably received by brackets 21 on the body of the car. Braces 22 connect the legs with the flooring of the platform. The starter when standing upon the platform has a clear view of the race track and the barrier strap 11. 30

An electric circuit 24 is provided for the actuation of the electrically operated catches 10 and also has connected in circuit therewith an electrical source 25 preferably in the form of a storage battery carried by one of the cars. The 35 electric circuit 24 extends from one car to the other by passing through a conduit 26 placed under the race track 1 and supported by the barrier tracks 3. Conductor take-up reels 27 are carried by the cars and they are connected in 40 the electric circuit referred to so that said cars may be moved along the barrier track without affecting the electric circuit. Also connected in the electric circuit and carried by the cars are 45 electric bells 28. The circuit is controlled by a switch 30 located in convenient reach of the starter from the platform. Thus it will be seen that the starter may conveniently release the barrier strap 11 by closing the switch 30 and simultaneously cause sounding of the bells 28 indicating that the race is under way.

The electric circuit 24 includes a plurality of conductors which are specifically set forth as follows: Conductors 10' and 11' are electrically con- 55

- nected to the catches 10, the latter including in their construction electromagnets, as shown in Figure 4, and one of the conductors 10' has a switch 30 electrically connected thereto and said 5 last-named conductor 10' is connected to the electrical source 25. The other conductor 10' is connected to the arm 14 of one of the cars 7 and the lower rail 6 engaged by the rollers 15 of said arm 14 is connected to a conductor 12' which connects 10 with the other rail 6 of the track. The arm 14 of the other car is connected to the electrical source by a conductor 13'. The conductors 11' are connected to the bells 28 and the latter are connected by a conductor 14' which is mounted 15 on the reels 27 of the cars. The conductors 12' and 14' pass through the conduit 26.

Having described the invention, I claim:

A movable race track barrier comprising car tracks located at opposite sides of a racetrack and each composed of upper and lower rails, cars mounted on said rails and each including a triangular-shaped body presenting an inclined face, handle bars secured to said bodies, barrier posts removably secured to the inclined faces and converging towards the race track, a barrier strap electrically released from the barrier posts, an 10 observation platform adapted to be removably mounted on one of said bodies, and an electric circuit including a source and a switch for the release of the electrically operated barrier strap. 15

TURNER C. RUSH.
